TUBE-FLARING TOOL

George E. Franck, Riverside, Ill., assignor to Imperial-Eastman Corporation, a corporation of Illinois

Filed Feb. 2, 1960, Ser. No. 6,142

1 Claim. (Cl. 153—81)

This invention relates to tube-flaring tools and in particular to manually operable tube-flaring tools.

Conventional manually operable tube-flaring tools are provided with the tube-clamping means for holding the tube fixedly during the flaring operation. It is desirable that the tool be adapted to flare tubes having any one of a plurality of different diameters, such as ranging from $\frac{1}{8}$ " to $\frac{3}{8}$ ". To provide such universality of use, clamping means have been devised including elongated clamping blocks having different diameter tube-clamping grooves spaced longitudinally therein. Alternatively, clamping means have been developed wherein the clamping blocks are relatively small and are provided with only one or two different tube-clamping grooves, the tool being arranged to receive selectively different ones of a plurality of such blocks to accommodate the full range of tube sizes. The disadvantages of relatively large size and resultant unwieldiness of the elongated block type clamping means, and the ease of loss of individual blocks in the individual small type block clamping means have been serious problems in the conventional tube-flaring tools.

Similarly, the means provided in the conventional tools for carrying the clamping blocks have not proven completely satisfactory. Lack of sufficient rigidity, lack of protection to the clamping blocks against chipping of the edges, etc., and slippage of the yoke from the clamping means are examples of such additional disadvantages of the conventional tube-flaring tools.

The present invention is concerned with a new and improved tube-flaring tool effectively eliminating each of the disadvantages of the conventional tools discussed above and providing an improved facility of use not found in the known manually operable tube-flaring tools.

It is the principal object of the present invention, therefore, to provide a new and improved tube-flaring tool.

Another object is to provide such a tube-flaring tool having a new and improved clamping block structure.

A further object is to provide such a tube-flaring tool having a new and improved carrier forming one portion of the tube-clamping means.

Still another object of the invention is to provide such a tube-flaring tool having a new and improved coacting yoke and clamping means structure.

A still further object of the invention is to provide such a tube-flaring tool which is compact, economically constructed, and which provides improved facilitated operation.

Other features and advantages of the invention will be apparent from the following description taken in connection with the accompanying drawings wherein:

FIG. 1 is a plan view of a tube-flaring tool embodying the invention, a portion of the handle being broken away to facilitate the illustration.

FIG. 2 is a transverse view thereof showing the yoke in side elevation and the clamping means in section taken

2

substantially along the line 2—2 of FIG. 1, and illustrating the arrangement of the tool upon completing the flaring of a tube end therein, the yoke being shown in dotted lines in a reverse arrangement for flaring a different diameter tube therein;

FIG. 3 is a rear elevation thereof partially in section taken substantially along the line 3—3 of FIG. 1; and

FIG. 4 is a fragmentary section taken substantially along the line 4—4 of FIG. 3, but with the blocks repositioned from the position thereof in FIGS. 1 through 3.

In the exemplary embodiment of the invention as disclosed in the drawing, a tube flaring tool generally designated 10 comprises a pair of clamping blocks 11 and 12, retained in a carrier 13, for holding a tube, such as tube 15, to be flared. The tool further includes a flaring cone 14 on one end of a rod 15 threadedly associated with one end 16 of a C-shaped yoke generally designated 17. The other end 18 of the yoke 17 is apposed to the flaring cone 14 to support the clamping blocks 11 and 12 during the flaring operation.

Tube-clamping blocks 11 and 12 are allochiral and cooperatively arranged to define eight different diameter tube-clamping structures to clamp selectively eight correspondingly different diameter tubes to be flared. To pro-

vide this desirable large number of different tube-clamping structures while yet permitting tool 10 to be extremely compact, the clamping blocks are provided with a generally square top surface 19 and a parallel generally similar bottom surface 20 defined by four side surfaces

21, 22, 23 and 24. Each side surface is provided with a pair of semi-cylindrical grooves which are axially perpendicular to the top and bottom surfaces and each of which corresponds to a different diameter tube. Illustratively, side surface 21 may be provided with a first groove 25 corresponding to a $\frac{5}{16}$ " diameter tube and a second groove 26 corresponding to a $\frac{7}{16}$ " diameter tube; side surface 22 may be provided with a first groove 27 corresponding to $\frac{1}{4}$ " diameter tube and a second groove 28 corresponding to a $\frac{1}{2}$ " diameter tube; side surface 23 may be provided with a first groove 29 corresponding to a $\frac{1}{8}$ " diameter tube and a second groove 30 corresponding to a $\frac{3}{8}$ " diameter tube; and side surface 24 may be provided with a first groove 31 corresponding to a $\frac{3}{16}$ " diameter tube and a second groove 32 corresponding to a $\frac{5}{32}$ " diameter tube.

Thus, when corresponding side surfaces of the tube blocks 11 and 12 are juxtaposed, the semicylindrical grooves thereof cooperate to form a pair of cylindrical tube-clamping structures corresponding to two different diameter tubes. Thus, depending on which of the side surfaces are juxtaposed, four different pairs of clamping structures may be formed.

The carrier 13, in which the clamping blocks 11 and 12 are retained, is arranged for facilitated positioning of the blocks in each of the four arrangements, and for facilitated application and release of the tube-clamping pressure to hold the tube end in the selected tube-clamping structure. More specifically, carrier 13 comprises a cast U-shaped member having elongated legs 33 and 34 provided with longitudinally extending grooves 35 and 36 respectively in which the edges of blocks 11 and 12 are slidably received. The thickness of carrier 13 perpendicular to the flat plane of the U configuration is constant other than at end 37 of leg 34, which end is bifurcated to define a pivot space 38. One end 39 of a

pressure bar 40 is pivotally mounted in space 38 on a split pin 41 having its opposite ends fixed in leg end 37. The height of bar 40 corresponds to the height of grooves 35 and 36 and to the height of clamping blocks 11 and 12. The distal end 42 of pressure bar 40 is provided with a slot 43 freely accommodating a bolt 44 which is pivotally mounted on end 45 of carrier leg 33 by a split pin 46. A wing nut 47 is threaded to the outer end of the bolt 44 and, when advanced against the pressure bar 42 with bolt 44 extending through slot 43, forcibly pivots the pressure bar in a counterclockwise direction as seen in FIGURE 1 to force the clamping blocks 11 and 12 toward the closed end 48 of the carrier, thereby clamping a tube end, such as tube end T, between the blocks in the pre-selected clamping structure of the confronting side surfaces.

Flaring cone 14 is carried on the threaded rod 15 which is moved longitudinally as a result of the rotation thereof as by a handle 48. The inturned end 18 of yoke 17 which is apposed to flaring cone 14 is spaced from mid-portion 49 of the yoke sufficiently to assure that it clears the carrier legs 33 and 34 permitting inner surface 50 to abut the bottom surface 20 of the clamping blocks and hold the clamping blocks against the substantial forces generated by the flaring cone 14 during the flaring operation. Inturned end 18 is further defined by an inner shoulder 51 and an outer shoulder 52 extending perpendicularly to the plane of end surface 50 and providing a positive abutment of end 18 with legs 34 and 33 respectively to prevent the yoke from inadvertently slipping from the clamping means.

As discussed above, each of the side surfaces of one clamping block is arranged to form with the corresponding side surface of the other block two different-diameter tube-clamping structures. As best seen in FIGURE 4, one clamping structure may be considered as being adjacent carrier leg 34 and the other clamping structure may be considered as being adjacent carrier leg 33. Referring now to FIGURE 2, it should be noted that when it is desired to flare a tube clamped in the clamping structure adjacent leg 34, yoke 17 is arranged to extend around leg 34 whereby the flaring cone 14 is generally aligned with the clamping structure adjacent the leg 34. Where the tube to be flared is clamped in the clamping structure adjacent the opposite leg 33, the yoke is reversely positioned, as shown in dotted lines in FIGURE 2, to extend around leg 33, whereby the flaring cone is automatically generally aligned with the clamping structure adjacent leg 33. Thus, for each position of the blocks 11 and 12 in the carrier, two tube-clamping structures are provided which may be selectively utilized by disposing the yoke 17 in the reversely alternative positions at opposite sides of the carrier. As best seen in FIGURE 2, the center of the end surface 50 midway between shoulders 51 and 52 is spaced further from yoke mid-portion 49 than is the axis of flaring cone 14. The axes of the groove pairs in each block side surface are oppositely spaced from the centerline of the side surface whereby the flaring cone is generally aligned with the selected tube-clamping structure when the surface 50 is centered relative to the blocks.

As indicated above, it is desirable that the flaring tool 10 be made compact. Toward this end, the longitudinal mid-portion 53 of each leg is provided with a segmental frusto-conical chamfer 54 accommodating a portion of the flaring cone 14 where the tube-clamping structure is closely adjacent the carrier leg. Further, as the support surface 50 is centered relative to the blocks when the cone axis is aligned with the selected clamping structure, a substantial support area is provided without interference with the carrier legs as would occur if the surface 50 and cone axis were directly aligned. As a result, the spacing 70 between legs 33 and 34 may be effectively minimized, permitting the size and weight of the clamping blocks as well as the carrier to be substantially reduced.

The use of flaring tool 10 is extremely simple. In illustrating the use thereof, it will be assumed that it is desired

to flare the end of a tube T having a nominal diameter of $\frac{5}{8}$ ". To clamp tube T in the flaring tool, the clamping blocks are arranged with surface 23 of clamping block 11 confronting the corresponding surface 23' of clamping block 12. Should the clamping blocks be disposed in carrier 13 with the other side surface in confronting relationship, such as shown in FIGURE 4, it is first necessary to rearrange the blocks to have the indicated relationship. To effect this, wing nut 47 is loosened on bolt 44 and bolt 44 is pivoted, in a counterclockwise direction as seen in FIGURE 4, to release support bar 40 and permit it to be pivoted on pin 41 in a clockwise direction to expose the open end of the U-shaped carrier 13. Blocks 11 and 12 are then removed from the carrier by sliding them longitudinally through grooves 35 and 36. The blocks are reinstalled with surfaces 23 and 23' confronting as shown in FIGURES 1-3. Pressure bar 40 is then swung in a counterclockwise direction as seen in FIGURE 1 into abutment with surface 21 of clamping block 11 and bolt 44 is swung in a clockwise direction to extend through slot 43 in the distal end 42 of the pressure bar 40.

The end of tube T is positioned in the tube-clamping structure defined by confronting clamping block grooves 30 and 30' to terminate substantially flush with the upper surface 19 of the clamping blocks. Wing nut 47 is then advanced on bolt 44 to bear against end 42 of pressure bar 40 and urge the pressure bar forcibly against clamping block surface 21, thereby forcibly clamping tube end T in the clamping blocks.

Yoke 17 is associated with the tube-clamping means as shown in FIGURE 2 to extend around leg 34 of the carrier 13, and handle 48 is manipulated to thread rod 15 downwardly through yoke end 16. Inturned end 18 of the yoke 17 is disposed to bear against the bottom surface 20 of the clamping blocks and support the clamping blocks against the substantial forces developed by the flaring cone 14.

Upon completion of the flaring operation, the flaring cone 14 is withdrawn by a retrograde manipulation of handle 48. Wing nut 47 may be loosened sufficiently to permit a spacing between clamping blocks 11 and 12 suitable to permit a withdrawal of the flared end of tube T. Should the subsequent tube to be flared be a $\frac{5}{8}$ " tube, or a $\frac{1}{2}$ " tube corresponding to the other groove of the pair in clamping block surfaces 23 and 23', the clamping blocks may be allowed to remain in the carrier, the subsequent tube end inserted in the appropriate tube clamping structure, the wing nut 47 retightened to fix the tube end therein, and the flaring cone brought into flaring engagement with the tube end by suitable manipulation of handle 48. Where the subsequent tube is a $\frac{1}{2}$ " tube, the yoke 17 need merely be reversely positioned on the carrier as shown in dotted lines in FIGURE 2 to effect the flaring of the tube in the clamping block structure defined by grooves 29 and 29'. Where the subsequent tube to be flared is one having a diameter other than $\frac{5}{8}$ " or $\frac{1}{2}$ ", the clamping blocks need merely be suitably repositioned, as described above, and the flaring operation effected as indicated.

While I have shown and described one embodiment of my invention, it is to be understood that it is capable of many modifications. Changes, therefore, in construction and arrangement may be made without departing from the spirit and scope of the invention as defined in the appended claim.

I claim:

In a tube-flaring tool, tube-clamping means including a pair of allochiral clamp blocks having generally square, parallel top and bottom surfaces defined by side surfaces each of which is provided with a pair of semicylindrical grooves axially perpendicular to said top and bottom surfaces, a U-shaped member having legs provided with mutually confronting longitudinal channels for slidably receiving the blocks with corresponding side surfaces confronting each other to define selectively four side-by-side

pairs of cylindrical tube-clamping grooves, means engaging the legs at the open end of the member operable to apply a tube-clamping force to the blocks, and a C-shaped yoke having one end carrying a flaring tool, a mid-portion, and an opposite inturned end extending through the space between the legs of the U-shaped member to abut removably the blocks and support the same against a tube-flaring force developed by said flaring tool, said inturned end being spaced from said mid-portion a distance preselected to permit the yoke to straddle selectively either leg of the U-shaped member with the inturned end substantially centered between said legs when the flaring tool is aligned

with the axis of either tube-clamping groove of the pair defined by the confronting semicylindrical grooves.
